C. H. HAESELER,
TOOL CLUTCHING MEANS FOR HAMMERS AND DRILLS.
APPLICATION FILED JULY 22, 1914.

1,181,383.

Patented May 2, 1916.

UNITED STATES PATENT OFFICE.

CHARLES H. HAESELER, OF PHILADELPHIA, PENNSYLVANIA.

TOOL-CLUTCHING MEANS FOR HAMMERS AND DRILLS.

1,181,383.

Specification of Letters Patent.

Patented May 2, 1916.

Application filed July 22, 1914. Serial No. 852,431.

To all whom it may concern:

Be it known that I, CHARLES H. HAESELER, a citizen of the United States, residing at Philadelphia, in the county of Philadelphia and State of Pennsylvania, have invented certain new and useful Improvements in Tool-Clutching Means for Hammers and Drills, of which the following is a specification.

10 My invention relates to means for clutching or gripping the working tools of different kinds as used in power hammers and drills and the object thereof is to provide simple and efficient means of this character capable of clutching or gripping tools having a collarless shank, that is a shank of substantially uniform cross section and unprovided with a collar or similar provision such as heretofore has been found necessary 20 in order that the tool may be held or secured in the hammer or drill.

In the present instance my invention is shown embodied in a drill of the percussive type whose reciprocating piston imparts its 25 blows upon the end of a drill steel which is held by said clutching means at the front end of the drill but in such manner that the drill steel or bit together with the gripping or clutching means will move bodily to permit of the proper action of the drill steel in the drilling operation. A hand-operated device is provided for acting upon said 30 means for disengaging the same from the drill steel to permit the latter to be removed from the drill.

The various features of novelty and utility in my invention will be apparent from the description hereinafter given.

In the drawing, Figure 1 is an elevation 40 of a drill embodying my invention, the lower part thereof in which my invention resides being shown in section; Fig. 2 a plan view of the clutching means on a larger scale than shown in Fig. 1 and with a portion of the top plate broken away; Fig. 3 a top plane of said clutching means with the plate removed; Figs. 4, 5 and 6 sections on the line 4—4, 5—5 and 6—6 respectively of Fig. 3.

50 While I have preferred to show my invention embodied in a power hammer and in a hammer of the percussive type, yet it will be understood that my invention is not limited to the particular construction or type of instrument but that I contemplate using my invention wherever applicable.

For convenience in description of my invention I will describe the same in connection with the particular type or construction of instrument shown.

The particular instrument illustrated in Fig. 1 is a power hammer of the percussive type including a cylinder 1 in which reciprocates the usual piston, not shown, and provided with a rotation motor contained within a casing 2 for rotating through suitable driving connections a tool holder 3 which rotates upon the extension 4 of the cylinder. The drill bit or steel 5 is angular in cross section and the tool holder 3 has a central bore which is correspondingly angular to receive the drill bit so that the rotations of the tool holder 3 are imparted to the drill steel. The general construction and arrangement of parts above referred to are illustrated in my prior application filed 75 June 8, 1914, Serial No. 843,724 for improvements in drilling machines.

The rotatable tool holder 3 is surrounded by a shell or casing 6 which is secured or clamped to the cylinder by means of the bolts 7. The outer end of the casing or shell is provided with a lateral flange 8 to which is secured a supplementary casing 9 containing the tool clutching or gripping means constituting my invention. This latter casing is itself provided with a flange 10 secured to the flange 8 in suitable manner as by means of the bolts 11.

The tool clutching or gripping means includes a block 12 having a central bore 13 corresponding in shape to the cross section of the drill bit 5 which fits fairly snugly within. This block is provided on the same diameter with two circular holes 14 which extend downwardly partway through the block and are inwardly inclined toward each other and toward the central bore 13. These holes communicate with such bore through V-shaped apertures 15 as shown in Figs. 5 and 6 and contain balls 16 which are downwardly spring-pressed by means of the springs 17 which bear at their lower or outer ends against the balls and at their upper ends against a plate 18 secured to the top face of the block. These balls in their lowermost position project into the central bore 13 or rather against opposite sides of the drill bit if inserted in such bore so that while the drill bit may be forced inwardly freely the balls will grip the bit and prevent it from being withdrawn.

The gripping means above described are normally upwardly or inwardly sprung within the cavity or chamber of the casing 9 by means of the coiled spring 19 with the result that when the piston strikes the bit and the latter is thereby forced outwardly the entire gripping means will move bodily in an outward direction by reason of its gripping action on the bit. The gripping means therefore has a limited or predetermined amount of movement which corresponds substantially with the amount of movement ordinarily possessed by a drill bit in actual operation and such gripping means are returned to normal position together with the drill bit by means of the spring 19.

For the purpose of releasing the gripping means or clutch from the drill bit to permit the latter to be withdrawn I provide suitable hand means which here consists of a sleeve 20 having a central bore through which the bit passes and which slides in and out of the front or outer end of the casing 9. This sleeve at its inner end is provided with a lateral flange 21 which seats against an inner annular shoulder 9^a of the casing and is normally held in such position by means of the spring 19 interposed between such flange and the block 12. This sleeve is provided with a longitudinal flange or extension 22 which is adapted to enter an annular recess 23 in the block 12 and in its extreme movement to come into contact with the balls 16 and to force the same upwardly out of clutching engagement with the drill bit. In operation the operator forces the sleeve 20 inwardly and thereby unclutches the drill bit whereupon the latter may be readily removed.

I claim:

1. In combination with a hammer of the percussive type, a casing at the front end thereof, a clutch device arranged within the casing to engage and hold the tool with respect to outward movement and mounted for bodily movement in a direction longitudinal of the tool, and resilient means for normally moving said clutch device inwardly within the casing.

2. In combination with a hammer of the percussive type, a casing at the front end thereof, and a clutch device arranged within the casing to engage and hold the tool with respect to outward movement and mounted for bodily movement in a direction longitudinal of the tool, said clutch device having means extraneous of the casing for moving such device to unclutching position.

3. In combination with a hammer of the percussive type, a casing at the front end thereof, and a clutch device arranged within the casing to engage and hold the tool with respect to outward movement and mounted for bodily movement in a direction longitudinal

of the tool, said clutch device being normally held inwardly within the casing with a yielding pressure.

4. In combination with a hammer of the percussive type, a casing at the front end thereof, and a clutch device arranged within the casing to engage and hold the tool with respect to outward movement and mounted for bodily movement in a direction longitudinal of the tool, and a spring arranged within the casing for holding the clutch device inwardly with a yielding pressure.

5. In combination with a hammer of the percussive type, a casing at the front end thereof, and a clutch device arranged within the casing to engage and hold the tool with respect to outward movement and mounted for bodily movement in a direction longitudinal of the tool, said device including a block provided with a bore to receive the tool shank and movable clutch members arranged within the block and adapted to project into said bore and to grip the tool shank.

6. In combination with a hammer of the percussive type, a casing at the front end thereof, and a clutch device arranged within the casing to engage and hold the tool with respect to outward movement and mounted for bodily movement in a direction longitudinal of the tool, said device including a block provided with a bore to receive the tool shank and also provided with circular holes one side of which enters said bore, and spring pressed balls in said holes and projecting into the bore to grip the tool shank.

7. In combination with a hammer of the percussive type, a casing at the front end thereof, and a clutch device arranged within the casing to engage and hold the tool with respect to outward movement and mounted for bodily movement in a direction longitudinal of the tool, said device including a block provided with a bore to receive the tool shank and movable clutch members arranged within the block and adapted to project into said bore and to grip the tool shank, and a spring for holding the block inwardly within the casing with a yielding pressure.

8. In combination with a hammer of the percussive type, a casing at the front end thereof, and a clutch device arranged within the casing to engage and hold the tool with respect to outward movement and mounted for bodily movement in a direction longitudinal of the tool, said device including a block provided with a bore to receive the tool shank and movable clutch members arranged within the block and adapted to project into said bore and to grip the tool shank, and a hand piece movable within the casing and extending extraneous thereof and adapted to be projected against the

clutch members to force them from gripping engagement with the tool shank.

9. In combination with a hammer of the percussive type, a casing at the front end thereof, and a clutch device arranged within the casing to engage and hold the tool with respect to outward movement and mounted for bodily movement in a direction longitudinal of the tool, said device including a block provided with a bore to receive the tool shank and movable clutch members arranged within the block and adapted to project into said bore and to grip the tool shank, and a hand piece movable within the casing and extending extraneous thereof and adapted to be projected against the clutch members to force them from gripping engagement with the tool shank, and a spring interposed between said block and hand piece to normally hold the former inwardly and the latter outwardly.

10. In combination with a hammer of the percussive type, a casing at the front end thereof, and a clutch device arranged within the casing to engage and hold the tool with respect to outward movement and mounted for bodily movement in a direction longitudinal of the tool, said device including a block provided with a bore to receive the tool shank and also provided with circular holes one side of which enters said bore, and spring pressed balls in said holes and projecting into the bore to grip the tool shank, and a hand piece movable within the casing and extending extraneous thereof and having a portion arranged to enter said holes and to contact with the balls and force them from gripping engagement with the tool shank.

40 11. In combination with a hammer of the

percussive type, a casing at the front end thereof, and a clutch device arranged within the casing to engage and hold the tool with respect to outward movement and mounted for bodily movement in a direction longitudinal of the tool, said device including a block provided with a bore to receive the tool shank and also provided with circular holes one side of which enters said bore, and spring pressed balls in said holes and projecting into the bore to grip the tool shank, and a hand piece movable within the casing and extending extraneous thereof and having a portion arranged to enter said holes and to contact with the balls and force them from gripping engagement with the tool shank, said block and hand piece having marginal flanges, and a spring interposed between said block and hand piece to normally hold the former inwardly and the latter outwardly.

12. In combination with a hammer of the percussive type, a casing at the front end thereof, and a clutch device arranged within the casing to engage and hold the tool with respect to outward movement and mounted for bodily movement in a direction longitudinal of the tool, said device including a block provided with a bore to receive the tool shank and also provided with circular holes entering said bore through V-shaped apertures, and spring pressed balls in said holes projecting through said apertures and into the bore to grip the tool shank.

CHARLES H. HAESELER.
